United States Patent Office

Des. 182,295
Patented Mar. 11, 1958

182,295

HAND CART

Karl O. Larson, St. Paul, Minn.

Application November 27, 1956, Serial No. 43,960

Term of patent 7 years

(Cl. D14—3)

FIG. 1

FIG. 2

FIG. 4

FIG. 3

I claim:

The ornamental design for a hand cart, as shown.
